Primary Examiner — Michael A Pratt(74) *Attorney, Agent, or Firm* — Endurance Law Group, PLC(57) **CLAIM**

I claim the ornamental design for a rifle stock, as shown and described.

DESCRIPTION

FIG. 1 is perspective view of a rifle stock according to the present invention;

FIG. 2 is another perspective view of the rifle stock;

FIG. 3 is a right side view of the rifle stock;

FIG. 4 is a left side view of the rifle stock;

FIG. 5 is a top view of the rifle stock;

FIG. 6 is a bottom view of the rifle stock;

FIG. 7 is a front end view of the rifle stock; and,

FIG. 8 is a butt end view of the rifle stock.

The broken line showing of aspects of the rifle stock is included for the purpose of illustrating environment and forms no part of the claimed design.

1 Claim, 6 Drawing Sheets(56)
